UNITED STATES PATENT OFFICE.

ERICK VON MEHREN, OF DULUTH, MINNESOTA, ASSIGNOR TO HOAR SHOVEL COMPANY, OF DULUTH, MINNESOTA, A CORPORATION OF MINNESOTA.

MECHANICAL SHOVEL.

Application filed October 12, 1925. Serial No. 62,005.

To all whom it may concern:

Be it known that I, ERICK VON MEHREN, a subject of the King of Denmark, residing at Duluth, in the county of St. Louis and State of Minnesota, have invented certain new and useful Improvements in Mechanical Shovels, of which the following is a specification, reference being had therein to the accompanying drawing.

This invention relates to mechanical shovels and has special reference to specific means for the manipulation thereof, and the shovel here illustrated and described is especially designed for tunnelling purposes where room for operating the device may be considerably restricted such as experienced in coal, iron, or other mines.

The principal object of the invention is to provide a shovel of this type having the maximum of efficiency both in digging and manipulating its load.

Other objects and advantages will appear in the further description of the invention.

Referring now to the accompanying drawing forming part of this application and in which like reference characters indicate like parts:

Figure 1 is a side elevation of one of the improved shovels with the dipper fully advanced in position for digging, and

Figure 2 is a slightly enlarged rear elevation showing the dipper in its fully retarded position, such position being indicated in dotted lines in Figure 1.

The shovel, as before stated, is of the tunnelling type, and comprises the tram car 1, carrying the turntable 2 of any well known construction, upon which is pivotally mounted the superstructure 3, this latter being preferably considerably narrower in construction than the tram car, providing room at one side thereof and above the car for convenient seating of the operator; such seat being illustrated at 4.

The superstructure 3 carries the operating motor or motors, which may be either air, electric, or gas, as desired, and, in Figure 1, one of the air motors is illustrated at 5 and the controlling valves of the two others are shown at 6 and 7, they being controlled by the levers illustrated at 8. By these motors the superstructure may be rotated in either direction, and the shovel reciprocated, their connections and operation not being here illustrated as they are well known in the art.

Within the upper side walls 9 of the superstructure 3 is a track in which is reciprocably mounted the carriage 10, it having a set of eight rollers or wheels 11 for nonfrictional engagement with the side walls 9.

The crowding motor, controlled by the valve 6, operates the carriage operating drum illustrated at 12, about which is wound the line 13, one end leading about the sheave 14 to the front end of the carriage 10, while the other end leads around the sheave 15 to the rear end of the carriage 10, as indicated in dotted lines.

Upon the forward end of the carriage 10 is pivotally mounted as at 17 the auxiliary dipper stick 18, and it pivotally carries, outboard of the end of the carriage as at 19, the dipper stick 20, having upon its forward end the dipper 21. To the opposite end of the dipper stick as at 22 is attached the operating line 23, which may be either a line or chain as desired. This leads over the roller 24 upon the free end of the auxiliary dipper stick down to and about the sheave 25, pivotally mounted as at 26 within brackets 27 upon the upper end of the carriage 10, thence to and about the sheave 28, which is pivoted as at 29 in the rear upper end of the superstructure 3, thence to 85 a drum, operated by either one of the other two motors in the superstructure, said drum not being shown. By this means the dipper and operating sticks are controlled independently of the operation of the carriage, and the dipper controlling line 23, passing about the end of the auxiliary dipper stick 18 and directly down to and about the sheave 25 mounted upon the carriage, at all times pulls directly downwardly in 90 respect to the free end of the auxiliary dipper stick; this being true irrespective of the longitudinal position of the carriage upon the superstructure 3; whereas, in previously constructed shovels of this type, 95 where the line 23 leads directly from the free end of the dipper stick 20 over the auxiliary dipper stick to and about the sheave 28, the downward stress upon the free end of the auxiliary dipper stick was 100 considerably greater, and the benefits derived from the auxiliary stick much less appreciated in the digging manipulation of the dipper.

The rearmost end of the dipper stick 18 110

has depending therefrom a leg 29 from either side thereof, which, when the dipper stick is lowered in the position shown in dotted lines Fig. 1, rest upon the laterally extending webs 30 of the carriage 10, and the upward travel of the free end of the auxiliary dipper stick is limited by the chain 31, one end of which is attached to the dipper stick and the other end to the carriage.

10 The shovel here illustrated is shown with the tram car having wheels of greater diameter at one end than at the other, so as to give the superstructure an inclined position at all times which is not only beneficial in 15 the position of the shovel for digging purposes but also has a tendency to elevate same for loading into a tram car when the superstructure is rotated to a position opposite to that shown in Figure 1 of the drawing, this 20 however, being old in the art.

It is obvious that if a forward thrust of the carriage is desirable when the dipper is digging, the line 23 may be roven upon the opposite or rearmost side of the sheave 25 25 and about a sheave not shown on the shaft upon which the sheave 15 is mounted, and thence to the power mechanism.

Having thus described my invention, what I claim and desire to secure by Letters Patent, is:

1. In combination a tram car having a turntable thereupon, a power containing superstructure pivotally carried upon the turntable, a carriage reciprocably carried 35 within the superstructure, an auxiliary dipper stick pivotally carried upon the carriage, a dipper and dipper stick proper pivotally carried upon the auxiliary dipper stick, a dipper manipulating line attached to the 40 free end of the dipper leading over the dipper stick, downwardly about a sheave in the rear end of the carriage and thence to the

power mechanism within the superstructure.

2. In a mechanical shovel the combination with a vehicle, a superstructure supported to turn upon the vehicle, a track carried by the superstructure, a reciprocal carriage carried by the superstructure, an auxiliary dipper stick pivotally carried upon one end of the carriage, a dipper stick and dipper carried upon the auxiliary stick, a sheave in the opposite end of the carriage, and a single line for operating both of the sticks and in constant engagement with the sheave in the carriage.

3. A mechanical shovel comprising a rotatable structure, a travelling carriage mounted in said structure, an auxiliary stick pivotally supported upon one end of the carriage, a stick carrying a dipper pivotally supported on the auxiliary stick, and a flexible dipper operating means connected to the dipper carrying stick, bearing upon the free end of the auxiliary stick, and passing through the opposite end of the carriage, substantially as and for the purpose described.

4. The combination with a mechanical shovel comprising a vehicle having a turntable thereupon, a superstructure supported upon the turntable, an inclined track carried by the superstructure, a reciprocal carriage carried by the superstructure, an auxiliary dipper stick pivotally carried upon the carriage, a dipper stick and dipper carried upon the auxiliary stick, and a single line for simultaneously operating both dipper sticks, of means whereby the operating line is in constant engagement with the rear end of the carriage.

In testimony whereof I hereunto affix my signature.

ERICK VON MEHREN,
